UNITED STATES PATENT OFFICE

NICOLAS EMILIE MÉTHLIN, OF PARIS, FRANCE, ASSIGNOR TO SCHNEIDER & CIE., OF PARIS, FRANCE, A LIMITED JOINT-STOCK COMPANY OF FRANCE

DEVICE FOR DAMPING THE RECOIL OF THE BARREL IN GUNS OF ALL CALIBERS

Application filed May 25, 1931, Serial No. 539,916, and in France June 16, 1930.

In order to avoid impact shocks in guns, due to a too sudden running out of the barrel under the action of the recuperators, use is generally made at present of a run out valve 5 mounted at the end of the profiled counter rod upon which the piston rod of the recoil brake moves.

This valve which, during recoil, is in the open position and permits the braking liquid 10 to pass freely from the back to the front of the chamber formed at the end of the fixed brake rod, becomes on the contrary pressed on its seat as soon as the running out stroke commences and it thus permits the return of 15 the liquid from the chamber behind the piston into the brake cylinder to be restrained, as this return flow can only take place through the annular space left between the valve and the cavity in the brake rod.

20 Although this known device most frequently gives satisfaction in guns which are not employed for firing at high angles of elevation it does not give sufficient security in the case of guns designed for firing at angles 25 comprised between 0 and 90° in which the recuperator must return the gun to battery position and overcome the large vertical component of the weight of the recoiling mass.

30 In this case a powerful recuperator, although it permits the return to battery position to be effected without shock when firing at high angles, becomes too powerful when firing at low angles or on the horizontal; or, 35 stated more exactly, the normal valve for checking the running out stroke does not give sufficient security against impact shocks at the end of the return to battery position when firing under such conditions.

40 The object of the present invention is to provide a device which enables these disadvantages to be overcome.

The invention consists essentially of an additional valve combined with the main 45 valve and lodged in a cavity in the counter rod, which cavity communicates, through an axial duct in the said counter rod and through orifices which open into the said duct, with the annular space between the interior of the 50 brake rod and the counter rod.

The additional valve is normally maintained by the pressure of the liquid in a position in which it closes the axial duct of the counter rod, and it opens under the action of an opposing spring when, towards the end 55 of the return to battery position, the pressure which acts upon it has become suitably reduced.

Consequently, the liquid can at this 60 moment return from the brake rod chamber towards the brake reservoir through an increased section, the effect of which is to reduce the braking effect due to the main valve and permit the return to battery position to be completed in a sufficiently rapid manner 65 and without shock.

One practical form of construction of the invention is illustrated by way of example in the accompanying drawings:

Figures 1 and 1^a, when joined along the 70 broken lines, constitute a longitudinal sectional elevation of a recoil brake with counter rod and run out valve of known type, combined with the device forming the subject of the invention. In these figures the members are shown in the position they occupy at the commencement of the recoil of the barrel, 75

Figure 2 is a sectional elevation taken along the line 2—2 in Figure 1,

Figure 3 is a sectional elevation taken 80 along the line 3—3 in Figure 1,

Figures 4 and 4^a when joined along the broken lines constitute a sectional elevation of a part, corresponding to that shown in Figures 1 and 1^a, the members being shown 85 in the position they occupy at the commencement of the running out stroke,

Figures 5 and 5^a, when joined along the broken lines, constitute a similar view to that shown in Figures 1 and 1^a showing the members in the position they occupy towards 90 the end of the running out stroke.

In these figures, *a* is the cradle of a gun to which cradle the hollow piston rod *b* is connected by one of its ends; *c* is the brake 95 cylinder to which the profiled counter rod *d* is secured; *e* is the usual valve which serves to check the running out stroke by throttling the passage of the liquid from the chamber *b*¹ to the chamber *c*¹ of the brake 100

cylinder, the flow only taking place through the annular space left between the valve *e* and the internal wall of the rod *b*, on account of the fact that the valve *e* bears against the shoulder *d*¹ on the counter rod.

According to the invention, this known device for checking the movement of return to battery position is completed by the addition of a valve *f* lodged in a chamber *d*² formed in the counter rod *d*. This chamber *d*² communicates with the annular space *g* between the counter rod *g* and the hollow rod *b* through an axial duct *d*³ and two or more radial ducts *d*⁴ in the counter rod.

The valve *f* carries a collar *f*¹, which is adjustable in position and which is shown in elevation in Figure 3. In a notch *f*² on this collar engages one end of a spring *h* the other end of which bears upon the rear end of the chamber *d*². The valve *f* is hollow and comprises orifices *f*³ on its rear closed end. It will preferably be guided in the chamber *h* by fins *f*⁴.

When at rest, the members occupy the position shown in Figures 1 and 1^a; the main valve *e*, like the additional valve *f* preserves, with respect to the counter rod *d*, the relative position indicated in this figure, during the whole period of recoil.

As soon as the movement of return to battery position commences and the action of the recuperator intervenes, the brake cylinder commences to move with respect to the fixed piston; the pressure of the liquid in the chamber *b*¹ presses the valve *e* upon the shoulder *d*¹ (Figures 4 and 4^a): at the same time the valve *f* moves into the position shown in this figure, thus closing the communication between the chamber *b*¹ and the axial duct *d*³.

Towards the end of the running out stroke, at the moment when the usual valve *e* moves, in the recess *g* in the piston rod, into a position in which the annular space is considerably reduced, (Figures 5 and 5^a), the action of the additional valve intervenes on account of the fact that the pressure, in the chamber *b*¹, is at this moment suitably reduced, (on account of the reduction in speed of the mass returning to battery position) for the effect of the opposing spring *h* to become the greater and compel the said valve *f* to lift from its seat. A communication is consequently established between the chamber *d*¹ and the annular space *g*¹ through the cavity in the valve *f*, the orifices *f*³, the axial duct *d*³ and the radial ducts *d*⁴.

Consequently the liquid in the chamber *b*¹ will flow through a suitably enlarged section towards the brake cylinder, and from this moment the braking effect resulting from the action of the valve *e* is suitably reduced, so that the running out stroke can be completed without shock.

Claim:

A device for providing a greater safeguard against impact shocks occurring at the end of the running out stroke when firing at low angles of elevation, particularly in the case of guns capable of firing at high angles of elevation and provided with a recoil brake having a counter rod and run out valve (*e*), consisting of an additional valve (*f*) combined with the main valve and lodged in a cavity (*d*²) in the counter rod communicating through an axial duct (*d*³) in the latter and through orifices (*d*⁴) leading into this duct, with the annular space (*g*) between the interior of the brake rod and the counter rod, situated behind the said main valve, the said additional valve (*f*) being normally maintained by the pressure of the liquid in a position in which it closes the axial duct in the counter rod, while it is withdrawn under the action of a return spring (*h*) when the pressure of the liquid which acts upon it is conveniently reduced towards the end of the running out stroke.

In testimony whereof I have signed this specification.

NICOLAS EMILIEN METHLIN.
